THOMAS G. PIHLFELDT AND FELIX HARTUNG, OF CHICAGO, ILLINOIS.

OIL-CUP.

1,347,825.

Specification of Letters Patent. Patented July 27, 1920.

Application filed April 17, 1919. Serial No. 290,695.

To all whom it may concern:

Be it known that we, THOMAS G. PIHLFELDT, a citizen of the United States, residing at Chicago, in the county of Cook 5 and State of Illinois, and FELIX HARTUNG, a subject of Great Britain, residing at Chicago, in the county of Cook and State of Illinois, have invented a new and useful Improvement in Oil-Cups, of which the following is a specification.

The present invention relates to an improvement in oil-cups, and more particularly to that type of oil-cups wherein means are provided for the forcible expulsion of 15 a quantity of oil and for the continued slow feeding of oil from a reservoir maintained therein.

The invention is fully set forth and explained in connection with the several embodiments thereof illustrated in the accompanying drawings, in which—

Figure 1 shows in section one form of construction embodying the invention;

Fig. 2 shows in section a modified form 25 of construction embodying our invention; and

Fig. 3 illustrates an additional modification together with means for supplying oil thereto.

30 In the embodiment of the invention as shown in Fig. 1, the numeral 5 designates the body of an oil-cup, the lower portion of which is extended as a substantially cylindrical, threaded nipple 6, a suitable intermediate squared or hexagonal portion 7 being provided to facilitate the attachment of the cup in its desired location. A central bore is provided through the projecting attaching means 6 and 7 to permit the exit of 35 oil. Internally of the cup an upwardly projecting boss, or cylindrical body 8, is provided, which boss extends partially into the cup and is spaced from the side walls thereof to provide an oil reservoir between 40 it and the walls of the cup. The central bore of this boss or projecting member 8 forms an continuation of that of the members 6 and 7.

45 At its upper end the oil-cup body 5 is provided with a plurality of V-shaped annular grooves 9 of slight depth, and in addition a deeper annular groove 10 of rectangular cross-section which is pressed into the cup or so formed as to provide a circular 50 shoulder near the top of the cup. In the

larger groove 10 a packing ring 11, preferably of light, resilient steel, is provided. The shallow grooves 9 together with the packing ring 11, which latter may, however, be omitted, co-act with the long depending skirt 12 of the cap 13 to form a seal for the oil. This skirt likewise protects the cup against the entrance of dirt, water, etc. The cap 13 is retained upon the cup by means permitting a relative movement 60 with respect thereto, said means being illustrated as a rod 14 which is hooked or otherwise attached to an eye 15 riveted to the cap, and which extends downwardly into the central bore in the inwardly projecting 70 boss 8 and externally projecting members 6 and 7. This rod 14 is provided at its lower end with an eye 15' through which extends a pin 16 which engages the inwardly extending flanges of the ring 17. The upper surface of this ring forms a seat for a coiled spring 18, the other seat of which is formed by the shoulder 19 formed within the bore of the upwardly projecting boss 8. The cap is thus retained upon the cup 80 and is permitted a relative movement with respect thereto, the spring 18 tending to hold the cap seated upon the cup. A suitable washer 13', for example, of leather, is provided between the edge of the cup and 85 the cap.

In order to retain a reservoir of oil within the cup when the latter is positioned upon its side, a ring 20, formed to provide an internally projecting truncated cone, is seated 90 upon the upper shoulder formed within the cup by the groove 10. An opening 21 in the wall of the cup, normally covered by the skirt of the cap, permits the supply of oil to the cup when the cap is partially raised. 95 To prevent suction upon the oil in the cup when raising the cap, a conical opening 22 is provided in the top of the cap and is normally closed by the plug 23 mounted on the light leaf-spring 24 which is riveted to 100 the cap together with the eye 15. To provide for the slow feeding of the oil from the reservoir within the cup, an opening 25 is bored or drilled from the lowermost point in the annular space between the inwardly 105 projecting boss 8 and the walls of the cup 5, and this opening or bore is plugged by means of the felt wad 26.

In using the cup the cap is raised until the skirt clears the opening 21. The cup is 110

then filled with oil. The cap is thereupon pushed down to its seat, the air pressure thus produced within the cup forcing the oil through the exit. By one or more reciprocations of the cap the oil may be forced out of the cup until its level is lowered to the top of the inwardly projecting boss 8 within the cup. The annular space surrounding this boss then acts as a reservoir from which a slow feed through the opening 25 containing the felt plug 26 into the oil exit takes place. It is apparent that the oil supply opening 21 may be omitted and the cup filled by lifting the cap until its skirt clears the top of the cup and permits the supply of oil directly thereinto.

When the cup is used in the horizontal position, the inwardly projecting conical ring 20 acts, together with the inwardly projecting boss 8 at the base of the cup, to maintain an oil reservoir within the cup.

In the modification of the device shown in Fig. 2, the direct pressure of a plunger is utilized to forcibly expel the oil from the cup. In this figure, 35, indicates the body of the cup, which is formed with a downwardly projecting stem comprising the threaded portion 36 and the squared or hexagonal portion 37 and with the inwardly projecting boss 38, which is spaced from the walls of the cup 35 to form an annular oil reservoir therein. At its upper end the cup is provided with the shallow V-shaped grooves 39 and the deeper groove 40 intended for the reception of a packing ring 41, if the use of a packing ring is found desirable. The cap 42 is provided with an extended skirt 43 which co-acts with the grooves 39 and the packing ring 41 to form an oil seal and which normally covers the filling opening 44 formed in the wall of the cup. The plunger 45 which reciprocates within the cup, is provided with an upwardly extending stem 46 which is riveted to the top of the cap 42. A bore 46^a extending from the lowermost point in the cup between the upwardly projecting boss 38 and the walls of the cup 35, and containing the felt plug 47, permits of the slow egress of oil from the reservoir in the cup. The upper edge of the body of the cup 35 is spun or burred over to form the seat 48 for the coiled spring 49, the other seat of which is against the upper face of the piston 45 and which tends to force the piston downwardly in the cup.

The present form of construction is operated in substantially the same manner as that previously described, the cap being lifted so that its skirt and the plunger both clear the filling opening 44 in order to fill the cup, and the cap then being forced down, together with the plunger, to expel all the oil in the cup above the upper edge 65 of the inwardly projecting boss 38. The

oil remaining in the annular space surrounding this boss slowly feeds out through the felt plug 47 in the aperture 46.

It is readily apparent that oil-cups constructed in accordance with the present invention may be placed at various necessary points requiring oiling, for instance, on an automobile or a tractor, and may be fed from a central oil supply. This is illustrated by Fig. 3 of the drawings, in which 70 55 indicates an oil-cup substantially identical in construction, with the exception of oil-supplying means, with the cup of Fig. 2. As illustrated in the drawings, the filling opening in the wall of the cup is here omitted and the following mechanism used to supply the cup with oil.

The external screw-threaded portion 56 of the cup is here provided with a laterally extending arm 57 having a bore communicating with the oil exit bore of the cup. A coiled spring 58 and a ball 59 are inserted in this bore and co-operate with a seat on the reducing union 60 to form a ball-check valve which permits the ingress of oil to the cup, but prevents egress through this opening. By any suitable system of tubing, illustrated in dotted lines in the drawing, this lateral extension is connected with the central supply of oil, which is illustrated as a cup 61 95 provided with a skirted cap 62 retained in position on the cup by spring pressure and provided with a valve 63 to prevent the central oil-cup from becoming air-bound.

The cup 55 is provided at the end of the screw-threaded extension 56, which communicates with the bearing to be supplied with oil, with a ball-check 64, which prevents the suction of oil from the bearing back into the cup.

Although we have described our invention in connection with certain specific embodiments thereof, it is clearly apparent that the said invention is not limited to the specific forms of construction shown therein, except in so far as such limitations are contained in the accompanying claims.

We claim:

1. An oil-cup comprising a body formed with external and internal projections having communicating bores forming an oil exit, the internal projection being spaced from the walls of the body of the cup to form an oil reservoir therein, a bore extending from said reservoir to the oil exit, a 115 fibrous plug in said bore and means for exerting an expulsive force on the oil in the cup whereby oil above the internal projection may be forced out through the bore therein.

2. An oil-cup comprising a body formed with an oil exit and an internally projecting boss spaced from the body of the cup and having a bore communicating with the oil exit, an internally projecting flange in 125

said oil-cup adapted to coöperate with said boss to form an oil reservoir when the cup is in horizontal position, and means permitting passage of the oil from the reservoir to the oil exit.

3. An oil-cup comprising a body having an oil exit and an internally projecting boss spaced from the walls of said body to form a reservoir, said boss having a bore communicating with the oil exit, a bore being provided in said body extending from the oil reservoir to the oil exit, the latter bore being provided with a fibrous plug, and a reciprocating cap for said cup capable in its reciprocating movement of exerting pressure upon the oil in the cup.

4. An oil-cup comprising a body having an oil exit and an inwardly projecting boss spaced from the walls of said body to form a reservoir, the boss being provided with an opening communicating with the oil exit and the body being provided with an opening extending from the reservoir to the oil exit, a fabric plug in the latter opening, a cap for said cup, said cap being provided with a skirt extending over the body of the cup, the body being provided with a filling opening normally covered by the skirt of the cap.

5. An oil-cup comprising a body portion

having an outwardly projecting nipple and an inwardly projecting boss spaced from the walls of said body to form a reservoir, the boss and the nipple being provided with communicating openings forming an oil exit and the body being provided with an opening extending from the reservoir to the oil exit, a fabric plug in the latter opening, means attached to said nipple for supplying oil through the opening therein when suction is produced in the cup, and means for producing suction and compression in the cup.

6. An oil-cup comprising a body-portion having an outwardly projecting nipple and an inwardly projecting boss spaced from the walls of the body to form a reservoir therein, said boss and nipple having communicating openings forming an oil exit and the body portion being provided with an opening extending from the reservoir to the oil exit, a cap fitting over the body portion of the cup, a rod attached to said cap and extending through the oil exit openings, and a coiled spring seated within said openings and exerting pressure by means of said rod on the cap tending to retain it in position.

THOMAS G. PIHLFELDT.
FELIX HARTUNG.
